UNITED STATES PATENT OFFICE.

CLARENCE Q. PAYNE, OF NEW YORK, N. Y.

PNEUMATIC CONCENTRATING-TABLE.

1,068,163.

Specification of Letters Patent. Patented July 22, 1913.

Application filed August 14, 1912. Serial No. 715,006.

To all whom it may concern:

Be it known that I, CLARENCE Q. PAYNE, a citizen of the United States of America, residing in the borough of Manhattan, city, 5 county, and State of New York, have invented certain new and useful Improvements in Pneumatic Concentrating-Tables, of which the following is a full and true description.

My invention relates to improvements in 10 that type of concentrating table which separates crushed ores, and other mineral aggregates in a dry state, by reason of differences in the specific gravity of their associated minerals, when they are acted on by air 15 under pressure, while being subjected to mechanical agitation.

It embraces a novel and more durable medium for the table-top than any heretofore employed for this purpose. This medium 20 consists preferably of plates of accreted mineral particles forming a porous mineral septum, which while offering resistance to the passage of material through it, is permeable to air. It is also resistant to abrasion from 25 material passing over it, and is especially adapted to the treatment of material in a fine state of division, and also of material which has been heated in drying it. By my invention the table-top is also utilized to 30 equalize and control the air-pressure as it passes through it. In this way the air-pressure is enabled to act uniformly over a large area, thus securing more efficient results in separation.

35 In the accompanying illustration, Figure 1 shows in cross-section a view through a table-top, in which a novel medium for the latter is used: viz., porous silica plates or a similar mineral septum, through which air 40 is made to pass. Figs. 2, 3, 4, 5 and 6 show the application of my invention to two different types of concentrating tables.

It has heretofore been customary to use 45 for the previous top of pneumatic concentrating tables, some form of textile material, such as single or double woven cotton cloth, through which the air under pressure is made to pass, in order to permeate and agitate the ore-mixture which is made to travel 50 over its surface, in the process of separating it. Such material, however, while light and inexpensive in first cost, has serious disadvantages. Being much softer than the ore- 55 particles which travel over it, the fibers of the cloth are rapidly cut and abraded, and frequent stoppages and delays for renewal

of the top become necessary. Moreover, the openings between the meshes gradually become choked with fine particles, either from the material passing over the surface of the 60 top, or from impurities contained in the air which is made to pass through it from the under side. This "blinding" of the cloth-top interferes with the proper and uniform action of the air upon the ore-mixture, and 65 thus renders the separation intermittent and difficult to control.

In my invention I employ porous mineral plates for the medium of the table-top as 70 illustrated in Fig. 1. These plates are preferably made of finely crushed and granular particles of silica fused together with a binder, and left in an open or porous condition either by incomplete fusion, or by the removal of a volatile substance in the process of firing. It is also possible to use other 75 mineral substances, such as natural or artificial pumice, porous clay-brick or tiles, etc., the latter more especially for the treatment of fine material, but in general it is desirable 80 to select a material which is harder than the material of the ore-mixture to be treated on it, and which is not so dense as to require too great an air pressure in passing the required volume of air through it. 85

A table-top made up of such plates as I have described may be defined in general terms as a mineral septum. The pores or openings in such a mineral septum are quite 90 irregularly scattered through its mass, and also irregularly connected, so that extremely fine material may be made to travel over its surface without passing through the septum, although the pores may be of greater diameter than the particles resting on it. For the 95 same reason, fine impurities contained in the air delivered to the underside of the mineral septum can be passed through it without choking or blinding the pores.

The porous silica plates are usually made 100 about one inch or one and one-half inches thick. The friction of the air passing through the irregular pores or passages in the plates causes the latter to act to a certain extent as pressure "equalizers," so that 105 the air-currents issuing from their upper surfaces are enabled to act upon the ore-mixture in a uniform manner over a large area. The advantages of a porous mineral septum for the table-top of a pneumatic concentrating table are, briefly, great durability, 110 due to the fact that the principal ingredient

is as hard, or harder, than the ore-mixture which is made to travel over it, and is not affected by heat or moisture; absence of choking, or blinding, of the septum, since the pores or passages may be of greater size than the ore particles, and finally, better control over the separation by equalizing and controlling the pressure of the issuing air currents over a large separating area.

10 As shown in Fig. 1, the ends of the porous mineral plates may be supported by means of light T irons 33, which are riveted to the frame 12 of the table. Their joints and ends are carefully cemented, so that the air from 15 the box below the table can only pass through the body of the plates.

My invention may be applied to various types of pneumatic concentrating tables. In Figs. 2 and 3 I have shown its application to 20 a form of table which covers certain further improvements, whereby the removal of the separated products from the table can be more readily controlled and effected, and which I have made the subject of a separate 25 application for Letters Patent, filed coincidentally herewith and bearing Serial Number 715,005, filed August 14, 1912. In this form of table, air is admitted to an inclosed box, 13, below the mineral plates, by means of the 30 pipe 15, which is connected with a pressure fan. The table is supported by hinged levers 11, to the foundation frame 10, and is given an inclination in the direction of its longitudinal axis, but without transverse inclination, so that an ore-mixture fed at its upper 35 end is allowed to occupy the full width of the table, and is made to travel lengthwise thereof.

The table is given a rapid reciprocating 40 motion by means of a convenient head-motion mechanism, such as is shown in Figs. 1 and 2. This consists of an eccentric 16, which operates toggle levers 17, 17, by means of a pitman 18, whereby the angle-lever 19, 45 pivoted at 20, moves the connecting rod 21, and with it the table, rapidly back and forth.

The ore-mixture, which should be carefully sized in advance, may be fed from any 50 convenient hopper, as shown at 24. As it is caused to travel lengthwise of the table, the combined effect of the upward air-currents through the fine pores and openings of the silica plates, or similar mineral septum, combined with the agitation, due to the shaking motion of the table, causes the minerals of the ore-mixture to separate, and to occupy 55 separate layers or strata on the table top, the heavy mineral forming the lower layer, 60 while the light gangue mineral forms the upper layer, as indicated in the sectional view in Fig. 3. As these stratified minerals reach the lower end of the table, the ore-sheet is preferably narrowed by the guides 65 25, 25, so as to thicken the ore-sheet, and to

70 permit the separation of the concentrate and tailing to be conveniently made along superposed levels, by means of the division plates 26, 26, which are operated by the adjusting rods and nuts 28, 28, held from the brackets 29, 29. By removing an intermediate or middling product at the junction of the separated strata, it thus becomes possible to secure a clean concentrate and tailing product.

75 My invention may also be applied to another type of concentrating table, as shown in Figs. 4, 5 and 6. In this form the tabletop is given a transverse inclination, with only a slight longitudinal inclination, so 80 that the stratified products may be separated from each other in thin bands, and then collected at the end and side of the table, as indicated in Fig. 4. Here air is admitted to an inclosed box 10, below the porous mineral 85 plates by means of a pipe 11, which is connected with a pressure fan. The table is supported by any convenient tilting mechanism, such as shown in Figs. 4 and 5. Here the upper end of the table is held by a hollow 90 shaft 12 in the bracket-support 13 to the foundation frame 14. The end of the hollow shaft 12 supports the bracket 15, which rotates about it, and to which is riveted the 95 spring-plate 16. The latter in turn supports the pin-brackets 17, 17, at its extreme ends, and these fit the ends of the shafts which are held to the frame 18, 18, of the table. The manner in which the ends of the spring-plate support the table brackets is shown 100 more clearly in Fig. 6.

105 The bracket 15 has an arm-extension which carries a threaded rod which engages in a nut held as the end of the bracket-arm. By rotating the hand wheel at the end of the rod the bracket 15, and with it the spring plate 16, and the entire table, can be tilted transversely at any convenient angle. Motion may be imparted to the table by any suitable head-motion mechanism, such as 110 shown in Figs. 4 and 5, and which is connected with the table by means of the connecting rod 19 operating through the hollow shaft 12. Here an eccentric 20 operates the 115 toggle levers 21, 21, by the pitman-rod 22, whereby the angle-lever 23, pivoted at 24, moves the connecting rod 19, and with it the table, rapidly back and forth, by slightly springing the plate 16. The lower end of the table may be supported by a single-hinged rocker-arm 25, which permits a forward motion of the table by rotation about the pivot 26, and also a transverse inclination by rotation about the pivot 27. At the same time, a slight vertical adjustment can 120 be secured by the hand-wheel nut and threaded rod 25. The table may be fed from a convenient hopper, such as that shown at 28, which is placed at the upper corner of the table. Guide pieces 29, 30 and 31 may 125 130

be conveniently placed as shown at the upper end of the table, to thicken the ore-sheet, and increase its agitation before it is allowed to "fan out" over the lower side and end of the 5 table.

The action of the air-currents through the porous mineral plates, aided by agitation due to the rapid shaking of the table, causes the minerals in the ore-mixture to stratify, 10 and their separation is then effected by the greater distance the lower layer, or heavy mineral, travels compared with the upper layer or light mineral, as they are propelled forward over the transversely inclined 15 surface of the table. Their relative positions are indicated by the areas bounded by the broken lines shown in the plan view of the table, Fig. 4. The separated products are then collected by guide pieces, whose positions can be adjusted along the end and side 20 of the table, as shown in Fig. 4.

My invention may also be employed in connection with other types of pneumatic concentrating tables, such as that in which 25 the separation of the stratified minerals of an ore-mixture is effected by superposed diagonal riffles, which guide the separated products to different sides or positions of the table.

Having thus described my invention, I 30 claim:

1. In a pneumatic concentrating table, a porous mineral septum composed of accreted mineral particles in plate form, in combination 35 with means for reciprocating said septum, means for passing air through said porous septum while it is in motion, and means for feeding material to be separated

upon the surface of said septum, substantially as described. 40

2. In a pneumatic concentrating table, a porous mineral septum composed of accreted mineral particles in plate form, which forms the top of an inclosed box in combination with means for passing air from said box 45 through the porous septum, means for reciprocating said box, and means for feeding material to be separated upon said septum, substantially as described.

3. In a pneumatic concentrating table, the 50 combination of a table-top formed of a mineral septum porous to air under pressure, means for feeding the material to be separated upon said table-top, means for passing air through said porous table-top, means for 55 mechanically agitating said table-top in a transversely inclined position, and guides for directing the separated strata of minerals into receptacles at the discharge edges of the table-top, substantially as described. 60

4. In a pneumatic concentrating table, a table-top formed of plates of accreted mineral particles, porous to air under pressure, in combination with means for mechanically 65 agitating said table-top while in a transversely inclined position, means for feeding the material to be separated upon said table-top, means for passing air through said porous table-top, and guides for directing the separated strata of minerals into receptacles at the discharge edges of said table-top, substantially as described. 70
